CAR DOOR

Carl Lute, Hammond, Ind., assignor, by mesne assignments, to The Youngstown Steel Door Company, Cleveland, Ohio, a corporation of Ohio

Application April 19, 1934, Serial No. 721,285

14 Claims. (Cl. 20—69)

This invention relates to car doors and is directed primarily to means for rendering such doors dustproof.

It is an object of this invention to provide means cooperable with car doors to effect a dust seal around the margins of the doors and which shall be inexpensive, simple in design and readily applicable by unskilled labor.

A further object is to provide flexible tubular sealing means and inexpensive fastening elements economical of assembly with said sealing means and rapidly and easily applicable to the members to which the sealing means are to be secured.

15 A further object is to provide tubular flexible sealing means and inexpensive fastening devices quickly and easily associated with the sealing means and having substantial bearing upon the sealing means.

20 Other objects will become clear as the description of the invention proceeds.

In the drawings forming a part of this specification

Figure 1 is a broken elevation illustrating the 25 invention applied to one type of lift door;

Figure 2 is a horizontal section taken on line 2—2 of Figure 1;

Figure 3 is a vertical section taken on line 3—3 of Figure 1;

30 Figure 4 is a section similar to Figure 3, showing the invention applied to another type of lift door;

Figure 5 is a horizontal section similar to Figure 2;

35 Figure 6 is a vertical section taken on line 6—6 of Figure 2;

Figure 7 is a detail plan view of one of the fastening devices; and

Figure 8 is a detail elevation of the fastening 40 device shown in Figure 7, a tubular sealing strip being shown in dot and dash lines in order to illustrate the mode of assembly of the fastening device with the sealing strip.

45 Applicant's novel dust-proofing arrangement and weather seal is shown utilized with the type of lift door illustrated in Figures 1, 2 and 3 of the drawings. The door illustrated is designated by the numeral 10 and comprises preferably a sheet metal panel 11 which may be provided with spaced horizontal corrugations 12 merging at their ends with vertical corrugations 13 and 14. A reinforcing marginal frame is secured to the metallic panel 11 and embodies an upper reinforcing member 15, disposed with one leg 16 thereof extending inwardly horizontally

toward the railway car 17 upon which the door is mounted. The reinforcing frame, additionally, includes a front vertical substantially channel shaped reinforcing member 18, a rear vertical reinforcing member 19 and a lower horizontal 5 reinforcing angle member 20.

As hereinbefore stated the door is preferably of the lift type whereby, in its closed and lowered position, said door is adapted to have frictional engagement with a supporting track 21 10 secured by means of a plurality of brackets 22 to the side sill reinforcing member 23 of the car. Frictional engagement for the door is effected through the medium of the lower reinforcing angle member 20, as best shown in Figure 15 3 of the drawings. In order to move the door the frictional engagement is broken and the door supported upon a plurality of rollers 24 constituting a portion of an elevating mechanism 20 designated as a whole by the reference numeral 25.

Referring to Figure 2 of the drawings it will be apparent that the forward movement of the door is terminated by the front stop member 26, which is secured to the front door post 27. At 25 the rear of the door a sealing strip 28 is secured to the inner face of the door and adapted to engage a spark strip 29 secured to the rear door post 30. The construction at the top of the door is clearly illustrated in Figure 3 of the drawings 30 and embodies a Z shaped side plate 31, to the depending leg 33 of which a substantially Z shaped retainer 34 for the top of the door is secured. The depending leg 33 additionally carries an angle member 35 disposed with its horizontal leg 36 extending outwardly so as to be overlapped by the inwardly extending leg 16 and the angle member 15 secured to the upper margin of the door.

40 For the purpose of providing a permanent and efficient dust seal for the door 10 it is preferred to utilize a nonmetallic tubular flexible sealing strip. In the closed position of the door the forward edge thereof is adapted to engage the sealing strip 37 secured to the front stop 26 in a 45 manner hereinafter indicated. At the rear vertical margin of the door the sealing strip 28 carried by the door is adapted to engage a similar flexible tubular sealing strip 38 fastened to the spark strip 29. A similar flexible sealing strip 39 is secured upon the outwardly extending leg 36 of the angle member 35, whereby the inwardly directed leg 16 of the door reinforcing angle 15 is adapted to bear upon and provide an 50 effective weather and dust seal for the upper 55

portion of the door when said door is in its closed and lowered position. The lower portion of the door is rendered weather and dust-proof by means of a flexible sealing strip 40 secured between the opposed faces of a threshold plate 41 and the horizontal leg 42 of an angle member 43 riveted to the upstanding leg of a side sill 44.

In order to rapidly and efficiently fasten the tubular sealing strips to their supporting members applicant's novel fastening device is utilized. The structure of this device is clearly illustrated in Figures 7 and 8 of the drawings. From these figures it appears that said device, indicated as a whole by the numeral 45, is substantially T shaped and comprises the oppositely extending flanges 46 and 47 and a securing shank 48. The flange 46, as shown in Figure 7 of the drawings, may have a sharpened end so as to form a prong for a purpose disclosed later. The flange 47 is offset as indicated at 49 relative to the flange 46 in the direction of the shank and is adapted to limit the extension of the fastener into the sealing strip and to provide a firm engagement between the fastener and the spark strip 29. The fastening device 45 may be formed of a wire which is semi-cylindrical in section being bent into the desired shape. However, said device may be formed as a stamping or in any other desired manner.

When the fastening devices are utilized to fasten the flexible tubular sealing strips to their supporting members, said sealing strips may previously be perforated in order to provide a series of slits extending through the wall of the sealing strips. However, if the flange 46 of the fastening device is in the form of a prong said flange may be utilized to pierce the wall of the sealing strips. The fastening devices are assembled with a sealing strip by projecting the flange 46 through the wall of said strip in order to dispose said flange interiorly thereof. The fastening devices may then be turned in order to effect engagement between the offset flange 47 and the exterior of the wall of the sealing strip. The shanks 48, each of which is shown in Figure 8 of the drawings as a split shank, are then inserted through openings provided therefor in the supporting member whereupon the legs 50 and 51 of the shanks may be bent in opposite directions, thereby securing the sealing strip to its supporting member. The disposition of the sealing strip, the flanges and shanks of a plurality of fastening devices 45 is clearly shown in Figure 6 of the drawings. It will be apparent from the showing of this figure that adjacent fastening devices are so arranged that the flanges 46 thereof extend in opposite directions and that a substantial bearing between said flanges and the sealing strip is obtained. If desired, the legs 50 and 51 of each of the shanks may be soldered or welded to the supporting member. A further characteristic of each of the fastening devices is illustrated in Figure 6 of the drawings as well as in Figure 8. It will be observed from these figures that the angular relationship between the flange 46 and the shank 48 of each of the fastening devices is less than a right angle. By this provision tight engagement between the sealing strip and its supporting member is had even though the legs 50 and 51 may not be properly bent into engagement with the supporting member.

The invention, in its application to a modified form of lift door 52, is illustrated in Figures 4 and 5 of the drawings. The lift door comprises a

sheet metal panel 53 reinforced along its margins by means of the Z shaped reinforcing members 54, 55, 56 and 57. In its closed and lowered position the door is adapted to be frictionally supported upon a Z shaped track 58. For movement toward open position the door is adapted to be elevated relative to the track by means of a lift mechanism indicated in its entirety by the numeral 59, whereupon the door is supported for antifrictional movement upon said track by means of rollers 60. It will be apparent from Figures 4 and 5 of the drawings that the inner face of the door is substantially plane and that said face of the door is adapted to cooperate with a preferably continuous flexible tubular sealing strip 61 secured to the car upon which the door is mounted adjacent to the edges of said door. The flexible sealing strip 61 is shown secured to the front and rear door posts 62 and 63, to the depending leg 64 of an angle member 65 secured to the side plate 66 of the car, and to the depending leg 67 of an angle member 68 fastened to the floor supporting member 69 which, in turn, is secured to the side sill 70. The fastening devices 45 hereinabove described are utilized in the manner set forth to secure said sealing strip to the car members noted. It will be apparent that as the door 52 assumes its closed position it will be forced inwardly toward the car side by means of indentures 71 provided in the track 58 so that said door will bear against the flexible sealing strip around its entire margin. While the arrangement for weather-proofing and dust-proofing purposes is illustrated and described in connection with lift doors, it will be readily apparent that the arrangement is applicable, as well, to the doors of the straight sliding type.

It is to be noted that with the arrangement disclosed the sealing strips present uninterrupted or uncut surfaces for engagement with door members.

It will be apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. Means for providing a seal between a side member and a door member movable relative to said side member, said means comprising a flexible tubular sealing strip disposed upon one of said members and a plurality of fastening elements for securing said sealing strip thereto, each of said elements comprising oppositely extending flanges, one of said flanges being positioned upon the inside of said tubular sealing strip and the other of said flanges upon the outside thereof, and means for securing said elements to said one member, the other of said members engaging said sealing strip for the purpose set forth.

2. Means for providing a seal between a side wall having a door opening and an outwardly extending flange above said opening and a lift door mounted for sliding movement upon said wall for closing said opening, comprising a flexible tubular sealing strip supported upon said flange, fastening elements having flanges extending into the portion of said sealing strip engaging said flange secured to said flange whereby the upper portion of said sealing strip presents a smooth uninterrupted surface and a flange provided on said door adapted to bear

upon the upper portion of said sealing strip in the closed and lowered position of said door.

3. Means for providing a seal between a door opening and a door for closing said opening, comprising sealing strips extending substantially around said opening and means for securing said strips to said car, said means comprising oppositely extending flanges and a shank, said sealing strip being disposed between said car and one of said flanges, the other of said flanges being disposed between said sealing strip and said car, said shank being fastened to said car, said door in closed position engaging said strips for the purpose set forth.

15 4. Means for providing a seal between a door and an opening controlled thereby, said means comprising a nonmetallic tubular sealing strip and fastening devices for said strip, said devices comprising a flange insertable substantially 20 radially into said tube and adapted to be disposed in engagement with the wall of said sealing strip adjacent thereto, a second flange positioned exteriorly of said strip and adapted to engage the wall thereof and a securing shank.

25 5. Means for providing a seal between a door and an opening controlled thereby, said means comprising a nonmetallic tubular sealing strip and fastening devices for said strip, said devices comprising a flange insertable into said tubular strip through the wall thereof and adapted to be disposed in engagement with the interior of said wall adjacent to the point of insertion of said flange, a second flange adapted for exterior engagement with said wall and securing means.

30 35 6. Means for providing a seal between a door and an opening controlled thereby, said means comprising a nonmetallic tubular sealing strip and fastening devices for said strip, said devices comprising a flange insertable into said tubular strip through the wall thereof and adapted to be disposed in engagement with the interior of said wall adjacent to the point of insertion of said flange, a second flange adapted for exterior engagement with said wall and securing means, the interiorly disposed flanges of adjacent devices extending in opposite directions.

40 45 7. Means for providing a seal between a door and an opening controlled thereby, said means comprising a nonmetallic tubular sealing strip and fastening devices for said strip, said devices comprising a flange insertable into said tubular strip through the wall thereof and adapted to be disposed in engagement with the interior of said wall adjacent to the point of insertion of said flange, a second flange adapted for exterior engagement with said wall and securing means, the interiorly and exteriorly disposed flanges being offset relative to each other in a direction transverse to said sealing strip.

50 55 60 8. Means for providing a seal between a door and an opening controlled thereby, said means comprising a nonmetallic tubular sealing strip and fastening devices for said strip, said devices comprising a flange insertable into said

tubular strip through the wall thereof and adapted to be disposed in engagement with the interior of said wall adjacent to the point of insertion of said flange, a second flange adapted for exterior engagement with said wall and a 5 securing shank extending from said flanges, said interiorly disposed flange forming an acute angle with said shank.

9. Means for providing a seal between a door and an opening controlled thereby, said means 10 comprising a nonmetallic tubular sealing strip and substantially T shaped fastening devices for said strip, said devices comprising a head flange insertable into said tubular strip through the wall thereof for interior engagement with 15 wall adjacent to the point of insertion of said flange, a second head flange adapted for exterior engagement with said wall and a securing stem.

10. Means for providing a seal between a door 20 and an opening controlled thereby, said means comprising a nonmetallic tubular sealing strip and fastening devices for said strip, said devices comprising a flange insertable into said tubular strip through the wall thereof for interior engagement with said wall adjacent to the point 25 of insertion of said flange and a securing shank.

11. Means for providing a seal between a door and an opening controlled thereby, said means comprising a nonmetallic tubular sealing strip 30 and fastening devices for said strip, said devices comprising a flange insertable into said tubular strip through the wall thereof for interior engagement with said wall adjacent to the point of insertion of said flange and a securing 35 shank, said shank extending from one end of said flange.

12. In means for providing a seal between a closure and an opening controlled thereby, said means embodying a sealing strip, fastening devices for said strip, said devices comprising a flange adapted to be extended through a wall of 40 said sealing strip and disposed in engagement with the opposite face of said wall and a securing shank.

13. Means for securing a sealing strip between a closure and an opening controlled thereby, said sealing strip having a tubular section, said means embodying a flange insertable into said section through the wall thereof and adapted 50 to be disposed in engagement with the interior of said wall adjacent to the point of insertion of said flange and a securing shank.

14. Means for securing a sealing strip between a closure and an opening controlled thereby, said sealing strip having a tubular section, said means embodying a flange insertable into said section through the wall thereof and adapted to be disposed in engagement with the interior 55 of said wall adjacent to the point of insertion of said flange, a second flange positioned exteriorly of said section and adapted to engage the wall thereof and a securing shank.

CARL LUTE.
